J. H. BOYE

COMMODITY CABINET

Filed March 19, 1923

Fig. 1.

1 Inventor:
James H. Boyce,
Brooklyn, N. Y., Chittenden, Vt.,
Att. P. M.

UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

COMMODITY CABINET.

Application filed March 19, 1923. Serial No. 626,120.

To all whom it may concern:

Be it known that I, JAMES H. BOYE, a citizen of the United States, residing at Chicago, in the county of Cook and State

5 of Illinois, have invented a new and useful Improvement in Commodity Cabinets, of which the following is a specification.

This invention relates particularly to a commodity-cabinet of a type in which a 10 rotary carrier is mounted in a suitable casing, such a cabinet being adapted particularly to the purpose of storing and dispensing small articles, such as needles, bobbins, shuttles, etc.

15 The primary object is to provide an anti-friction bearing for the carrier-shaft, which will permit the ready assembly of the parts and which will allow the necessary freedom of movement of the shaft.

20 The invention is illustrated in its preferred embodiment in the accompanying drawing, in which—

Figure 1 represents plan view of commodity cabinet embodying the invention; 25 and Figure 2, a broken vertical sectional view taken as indicated by line under my Figure 1.

In the construction illustrated, A represents a casing which comprises a base-section 30 1, and a cover section 2, these sections being formed of sheet metal and being provided with peripheral flanges which are telescopically connected; B, a shaft having its upper portion journaled in the top wall 35 of casing and having its lower end extending freely into a cup which is rigidly secured to the inner surface of bottom wall of said casing; C, a pointer or handle disposed above the casing top and rigidly secured to the projecting upper end of the 40 shaft B; D, a carrier-disk rigidly secured to the shaft B on which it is mounted, the carrier D being equipped with an internally toothed locking ring D'; E, a closure for a hand-opening E' with which the casing top 45 is provided, the closure E being equipped with a knob, by which means, the closure may be swung about the shaft B as a pivot; E", a shank with which the closure 50 is equipped, this shank being pivoted on shaft B; and F, a locking-bolt or slide which coacts with the locking ring D' in a well known manner.

In the illustration given, the base section 55 1 comprises a bottom disk 1^a and upturned

flange 1^b. Similarly, the cover section 2 comprises a top wall or disk 2^a and a down-turned flange 2^b. These flanges are in telescopic engagement as shown in Fig. 2.

The carrier disk D is formed from sheet metal and is provided with depressed central portion 5. The internally toothed ring D' is provided with clenching lugs 6, which extend through perforation in the sheet metal member D. 65

The bolt F is in the form of a sheet metal member which has rigidly secured to it a cam stud 7, the upper end of this stud engaging a cam slot 8 with which the shank E² of the closure is provided. The 70 member F is provided with a spearhead 9, which is adapted to interlock with the teeth of the ring D'. As long as the closure E is in the closed position, the carrier may be rotated freely. The rotation may be ef- 75 fected by turning the shaft B through the medium of the pointer or handle C. When the closure E swings to the open position after the carrier has been turned to any desired position, the cam-slot 8 engaging the 80 cam-stud 7 moves the bolt F to the locking position; thus, the carrier is held locked while the closure is in the open position. The manner of actuating the bolt is now 85 well understood in the art and need not be further described.

In the illustration given, the casing-top 2^a has secured to its inner surface, a bar 10, which together with the casing-top is provided with a perforation or bearing for 90 the upper portion of shaft B.

The bar 10 is provided with a down-turned flange 10^a which has therein, a guide-slot for the bolt F. The bolt F is provided with a slot 11, which engages the shaft B 95 and aids in guiding the bolt.

A dished sheet metal member 12 disposed below the depressed central portion 5 of the carrier D, has its peripheral portion 5. The member 12 is secured to the shaft B by 100 means of a pin 13. The member 12 serves to give additional strength and brace the carrier disk.

The cup 3 affords a bearing which is open at its upper end. This bearing is preferably formed from a rod or bar of suitable material. It is provided at its upper end with an enlarged bore 3^a, whose peripheral walls preferably diverge upwardly somewhat. The lower end of block or bearing 110

member 3, is provided with central perforation 3^b, the lower end of which is tapped or threaded. A short screw 14, passes through a central perforation in the bottom 5 wall 1^a and is screwed into the tapped portion of the perforation 3^b, the head of the screw bearing against the lower surface of the bottom wall 1^a. The central portion of bottom wall 1^a is struck upwardly as indicated 1^c. In the bottom of the bore 3^a of the cup is placed a loose disk 15, which has a rounded or part-spherical upper surface. This disk preferably, is provided with a short shank 15^a, which depends freely into 10 the perforation 3^b; thus, the disk 15 is free to turn in its socket in the event that sufficient friction is exerted by the shaft B to cause such turning of the disk. The lower end of shaft B is reduced in diameter as indicated 16, and the extremity or reduced portion is preferably enlarged and provided with a part-spherical end surface as indicated at 16^a. The part spherical 16^a bears on part spherical surface of the disk 15 in 15 the cup. It will be observed that the shaft is free to swing more or less from the strictly vertical position without causing binding in the cup-bearing 3.

In this connection it may be stated, that 30 while the perforation through the casing top and through the bar 10 affords bearing for the upper portion of the shaft, a close fit is not desired or practicable at this point; hence a certain amount of freedom of movement 35 of the shaft from a strictly vertical position is to be permitted by the construction at the bearing 3.

In the use of the cabinet, the carrier D is loaded with containers which contain small 40 articles of merchandise, such as the articles enumerated above. These small articles are usually contained in tubes or other suitable holders which are demountably carried by the carrier disk D.

45 In Fig. 2, one of the needle tubes, design-

nated 17, is shown brokenly, this tube passing through a perforation in the disk D and being provided with a flange 17^a which rests upon the disk.

When the carrier is loaded with merchandise, it supports a considerable amount of weight. In practice, these commodity-cabinets are supplied to dealers throughout the country, and a cabinet may be in daily use for years; hence, it is desirable to provide a simple and durable bearing which will permit the carrier to be turned with great ease and which will not readily get out of order.

The construction described is admirably suited to the purpose. The foregoing description has been given for clearness of understanding, and no unnecessary limitation should be understood therefrom.

What I regard as new, and desire to secure by Letters Patent, is—

In combination in a commodity-cabinet, a casing comprising a sheet-metal base section having a bottom wall and an upturned flange, a sheet metal cover-section, comprising a top wall and a down-turned flange, 70 said flanges being in telescopic engagement with each other; a cup having its upper end provided with an enlarged bore and having its lower end disposed adjacent to the inner surface of said bottom wall; a screw extending through said bottom wall and having threaded connection with said cup and securing said cup to said bottom wall; a disk mounted freely in the bottom of the bore of said cup; a shaft having its upper end 75 portion journaled in said top wall and having its lower end portion extending freely into said cup and provided with a part-spherical bearing surface engaging said disk; a carrier disk mounted on said shaft: 80 and an actuating arm disposed above the casing top and secured to the upper end of said shaft.

JAMES H. BOYE.
